US00D943465S

(12) **United States Design Patent** (10) **Patent No.:** **US D943,465 S**
Berman et al. (45) **Date of Patent:** **** Feb. 15, 2022**

(54) **ROLLATOR**

(71) Applicant: **Medline Industries, LP**, Northfield, IL (US)

(72) Inventors: **Emily Hannah Berman**, Park Ridge, IL (US); **William Elliott Brooks**, Chicago, IL (US)

(73) Assignee: **Medline Industries, LP**, Northfield, IL (US)

(**) Term: **15 Years**

(21) Appl. No.: **29/767,028**

(22) Filed: **Jan. 20, 2021**

Related U.S. Application Data

(63) Continuation of application No. 29/701,305, filed on Aug. 9, 2019, now Pat. No. Des. 908,550, which is a continuation of application No. 29/642,301, filed on Mar. 28, 2018, now Pat. No. Des. 857,561.

CLAIM

The ornamental design for a rollator, as shown and described.

DESCRIPTION

FIG. 1 is a front perspective view of our new design of a rollator in a first configuration;

FIG. 2 is a right side elevation view thereof, the left side elevation view being a mirror image thereof;

FIG. 3 is a top plan view thereof;

FIG. 4 is a front elevation view thereof;

FIG. 5 is a rear elevation view thereof;

FIG. 6 is a front perspective view of the rollator in a second configuration;

FIG. 7 is a right side elevation view thereof, the left side elevation view being a mirror image thereof;

FIG. 8 is a top plan view thereof; and,

FIG. 9 is a front elevation view thereof.

The broken lines illustrate portions of the rollator that form no part of the claimed design.

1 Claim, 9 Drawing Sheets
